(57) **CLAIM**

The ornamental design for a light, as shown and described.

DESCRIPTION

FIG. 1 is a perspective view of a light showing my new design; FIG. 2 is a side view of the light shown in FIG. 1; FIG. 3 is a bottom view of the light shown in FIG. 1; FIG. 4 is a front view of the light shown in FIG. 1; FIG. 5 is a side view of the light shown in FIG. 1, in an alternate position; FIG. 6 is a back view of the light shown in FIG. 1; and, FIG. 7 is a top view of the light shown in FIG. 1. The broken lines shown on the drawings depict environment only and form no part of the claimed design.

1 Claim, 7 Drawing Sheets
